UNITED STATES PATENT OFFICE.

FEODORE A. BERNHARD, OF NEW YORK, N. Y.

DESIGN FOR A BADGE.

SPECIFICATION forming part of Design No. 19,430, dated November 19, 1889.

Application filed October 28, 1889. Serial No. 328,476. Term of patent 3½ years.

To all whom it may concern:

Be it known that I, FEODORE A. BERNHARD, of the city, county, and State of New York, have invented and produced a new and original Design for Badges, of which the following is a full, clear, and exact description, reference being had to the accompanying drawing, forming part thereof.

My design consists of the diagonally-disposed strips *a a*, with dovetailed ends *d d*, and a strip *b*, pendent from beneath the apex of the said strips *a a*. Upon the apex of the

strips *a a* are disposed two loops *c c*, and above and below said loops are disposed strips *e*. The strip *b* is extended below the ends of the strips *a a*.

I claim—

The design for a badge herein described, and shown in the accompanying drawing.

FEODORE A. BERNHARD.
